FURNITURE COMPONENT WITH HARDENED
EXPOSED SURFACES

Carl Brynolf Lundstrom, Little Falls, N. Y.

Application April 17, 1944, Serial No. 531,432

3 Claims. (Cl. 20—0.5)

1

This invention relates to wooden furniture components and particularly that part of these components subjected to excessive wear or surface injury.

Typical examples are the exposed corners of center posts or the legs of desks, exposed edges of the writing bed or top of desks, arms or front edges of chairs and the like which are continually subjected to excessive wear or impact, causing rupture of the surface, often to the extent of splintering the wood itself. These surfaces when so ruptured often cause annoying damage or injury to the person or the apparel of the user.

The invention provides a component having an exposed surface or corner densified. From the method standpoint the invention contemplates giving this particular part its desired form or shape by compression of the outer fibers by the use of forming dies. To permit this compression it is necessary to start with a blank which is over-size to the extent of the relative compression that will take place during the shaping and densifying cycle.

This compression is actually accomplished by first plasticizing the section to be compressed, causing the lignin to release its grip on the cellulose fibres. The preferred mode of practicing the invention is, therefore, to start with the component part; over-size in cross-section, and then to plasticize to a moderate depth below the surface of the area to be densified, by the application of heat. The surface to be densified may be impregnated in advance with a resin forming compound that will act as a plasticizing agent when heat is applied. However, the natural moisture contained in most woods will, if properly controlled, serve as this plasticizing agent. The application of heat to the area to be densified will cause the softening of the wood at this point. The blank in this condition is then compressed to its final shape or form by the application of pressure through forming dies. The further application of heat is continued and as the critical temperature is reached, thermosetting takes place and the component will retain its changed shape permanently. By proper choice of dies, a final smooth surface is imparted to the component in which the grain of the wood has not been changed in appearance.

In this way the component is given a dense splinter-proof integral case or shell which matches other wooden parts, and can be stained or varnished or otherwise treated as desired.

Practical embodiments of the invention as applied to a desk leg or center post will now be

2

described by reference to the accompanying drawing. In the drawing:

Figure 1 is a diagrammatic end view of the over-size leg blank impregnated and associated with dies prior to pressing.

Figure 2 is a similar view showing the conditions at the completion of the pressing operation.

Figure 3 is a fragmentary perspective of the finished article.

10 Figure 4 is a view similar to Figure 2 suggesting a different configuration.

Figure 5 is a view similar to Figure 1 showing how veneer may be applied.

15 Figure 6 is a view similar to Figure 2 showing conditions after completion of pressing with the application of veneer as in Figure 5.

Figure 7 is a diagrammatic end view indicating the changes of form and dimension which occur in connection with the treatment and article 20 illustrated in Figures 1, 2, and 3.

In Figure 1 an over-size blank for a desk leg is indicated at 11. A blank of the size indicated would be about $\frac{1}{4}$ " to $\frac{1}{16}$ " larger in each transverse dimension than the finished article is intended to be. These dimensions are suggestive because the amount of compression depends upon the depth of treatment and the desired density. Approximate proportions suitable for most cases are indicated in Figure 7 where the dotted lines 25 represent the original outline of the blank, while the contour of the final article after densification is indicated in full lines.

As above suggested it is not always necessary to impregnate the wood with a resin forming compound. If such a compound is used, the depth of impregnation would be approximately that indicated in Figure 1 by the shaded area 12. Impregnation can be effected in various known ways, the simplest being a soaking operation for a suitable period. Those woods which will develop a permanent plastic bond without impregnation are brought to a proper moisture content and this is usually a high moisture content. To expedite the pressing operation the surface 30 can be preheated to a moderate extent before introduction into the press.

The blank prepared as above described may be compressed between a sustaining die 13 and a heated forming die 14 against which the surface 35 to be densified rests. In the example illustrated in Figures 1 and 2 the forming die 14 has a filleted corner 15 designed to compress the corner 16 of the blank into a rounded surface which is even more dense than the adjacent surfaces because of the extra condensation of the wood

which there occurs. If the blank is not preheated the pressure is applied slowly so that the heat from the forming die will be transferred to the blank before heavy pressure occurs. If the blank has been preheated the pressure can be applied somewhat more rapidly.

The form assumed at the completion of the pressing operation is indicated in Figure 2. When the resin sets, the blank retains its compressed form and the densified surface is finished so far as form and surface are concerned. The completed leg or corner post is indicated in Figure 3. In this figure, 17 and 18 represent densified surfaces which meet in the even more markedly densified corner 19.

In Figure 4 a somewhat different contour is suggested, the purpose being to indicate, as is shown at 21, the possibility of producing molded sections having reentrant angles and even sharp protruding corners.

A significant thing about the procedure is the fact of surface densification and the fact that the wood article is changed to a different final form by a pressing operation which produces this final form and which creates the final surface texture. If not impregnated with a resin forming substance or if impregnated with a suitable resin forming substance such as urea combined with methylolurea, a wooden article so treated will take stain and can be varnished or otherwise treated. After such treatment it matches untreated portions of the wood, that is portions which have not been densified, and this fact is of the utmost importance in furniture which, to use a boat-builders' term, is finished "bright."

If it is desired to apply veneers, this is possible according to procedure indicated in Figures 5 and 6. In these Figures the blank is indicated at 22 in Figure 5 and is impregnated with any suitable plastic which will function as a glue. Many such are available. The veneer 23, which may, if desired also be impregnated with a similar plastic, is assembled with the blank in the die as shown in Figure 5. When subjected to pressure, the parts assume the form shown in Figure 6, and if the lower die is properly heated, the veneer will be bonded to the blank, and the veneer and also a portion of the surface of the blank will be densified as already suggested. As indicated in Figures 5 and 6 the veneer is slightly over-size until after the completion of the pressing operation whereupon the excess is trimmed away. In applying veneer as above described it is convenient to preheat the blank to which the veneer is applied so that it will be comparatively soft.

While several embodiments have been described in some detail, these are examples and do not limit the scope of the invention which can be variously applied to various different furniture components.

The form of the die to be used is subject to considerable variation. Any die and press which will develop the necessary pressure and permit the necessary application of heat concurrently with pressure may be substituted. Different woods will require to be treated in slightly different ways, but these involve matters of detail, the general principle of the invention being applicable as described.

What is claimed is:

1. A wooden furniture component comprising a straight strip with the grain thereof running longitudinally, said strip having an exposed rounded corner and a flat side tangent thereto, both corner and side being transversely condensed and densified to extend a distance beneath the surface thereof without material change in the external shape or the appearance of the grain, the densifying of the corner portion being greater and extending deeper than that of the side, the fibers of the densified portions being permanently bonded in such state, and the body of the strip being free from densification.

2. A wooden furniture component comprising a strip with the grain thereof running longitudinally, said strip having an exposed rounded corner and a flat side tangent thereto, both corner and side being transversely condensed and densified to extend a distance beneath the surface thereof without material change in the appearance of the grain, the densifying of the corner portion being greater and extending deeper than that of the side, the fibers of the densified portions being permanently bonded in such state and the body of the strip being free from densification.

3. A wooden furniture component comprising a strip with the grain thereof running longitudinally, said strip having an exposed corner and at least one adjacent face densified, said corner being more markedly densified than said face, the densification being evidenced by compression in a direction transverse to the grain of the wood, the fiber of the wood being bonded in such compressed state, the body and the remaining surface of the component being substantially free from densification.
